UNITED STATES PATENT OFFICE.

HUBERT C. SMITH, OF ST. LOUIS, MISSOURI.

MATTRESS-FILLING MACHINE.

Application filed November 27, 1925. Serial No. 71,639.

This invention relates to mattress filling machines, and has for its main object to provide a machine that can be used for filling the longitudinally divided casing or tick of a hinged mattress such as are used with folding couches and davenports.

Another object of my invention is to provide a machine that can be used for filling conventional mattress ticks or casings of various widths and also for filling the casing of a hinged mattress.

Figure 1 of the drawings is a vertical longitudinal sectional view of a mattress filling machine constructed in accordance with my invention.

Figure 2 is a top plan view of said machine.

Figure 3 is a front elevational view; and

Figure 4 is a detail transverse sectional view, taken on the line 4—4 of Figure 2.

Referring to the drawings which illustrate the preferred form of my invention, A designates the bed of the machine on which the material used to fill the mattress is placed, said bed being equipped with side pieces, B designates the pressing device that is used to compress, compact or pack down the material on the bed of the machine, C designates the spout at the discharge end of the bed over which the open end of the mattress tick or casing α is drawn, as shown in Figure 1, and D designates the pusher that is used to force said compressed or compacted material through the spout C into the mattress tick or casing. In order that the machine may be used for filling conventional ticks or casings varying in width from 26 inches to 56 inches, the bed A of the machine is made up of a number of loose boards 1, one or more of which can be removed when it is desired to reduce the width of said bed, the spout C is constructed in such a manner that the width of same can be varied to correspond with the width of the bed and the pusher D is provided with a removable section D' that can also be adjusted laterally of the bed so as to make it correspond in length to the width of the bed. Any suitable means can be used for moving the pusher longitudinally of the bed, such, for example, as a sprocket chain 2 connected to the pusher D, and the pressing device B can be constructed and arranged in various ways, the pressing device of the machine herein illustrated being supported at its rear end by a hinge 3 and having its front end

connected to a sustaining device 4 which is adapted to be lowered so as to cause said pressing device to move downwardly from the position shown in broken lines in Figure 1, and thus press or compact the material positioned on the bed A of the machine.

In order that the machine may be used for filling a hinged mattress tick such as is used in folding davenports and couches and which consists of a casing whose interior is divided into two compartments by a seam that extends longitudinally of the tick at the center of the same, I have equipped the machine with a removable dividing bar E

which is provided at its front end with a means that divides the spout C of the machine into two separate and distinct portions that are adapted to enter the two compartments of a longitudinally-divided mattress tick or casing. In the form of my invention herein illustrated the means just referred to is formed by two spout members 5 on the front end of the dividing bar E arranged in spaced relation so that they will straddle the seam at the center of a longitudinally-divided tick or casing which is drawn over the spout, as shown in broken lines in Figure 2, the central portion of the spout C being cut away at 6, as shown in Figure 2, so as

to receive the center seam or longitudinally-disposed dividing element of the casing positioned on the spout. The dividing bar E can be retained in operative position on the bed of the machine in any suitable way, as, for example, by a removable pin 7 that projects downwardly through said bar into the bed A, and the adjustable section D' of the pusher is provided with a hole for receiving the dividing bar E so as to permit the pusher to travel back and forth longitudinally of the bed of the machine when the dividing bar E is in use.

When the dividing bar E is arranged in operative position, as shown in Figure 1, the downward movement of the pressing device B compresses or compacts the material on the bed of the machine into two separate and distinct batches that are separated from each other by the dividing bar. Thereafter, when the pusher D moves forwardly said separate batches of material will be forced longitudinally of the bed through the spout C into the two compartments of the divided mattress tick or casing whose open end is arranged over the spout of the machine with the center seam or division of said casing

positioned between the two spout members 5 on the dividing bar E, thereby causing the two compartments or sections of the tick to be filled at one operation, and consequently, 5 reducing the cost of constructing hinged mattresses. When it is desired to use the machine to fill a conventional mattress tick or casing it is only necessary to remove the dividing bar E from the bed of the machine, 10 thus re-converting said bed into a single zone and re-converting the spout C into one wide spout which corresponds to the width of the batch of the material that is compressed when the pressing device B is moved 15 downwardly towards the bed.

While I have herein illustrated my invention embodied in a conventional mattress filling machine that can be converted into a machine which can be used for filling a longitudinally-divided tick or casing, such as is 20 used with a hinged mattress, I wish it to be understood that one feature of my invention consists of a mattress filling machine provided with any suitable means for compressing or compacting two batches of material; and any suitable means for thereafter forcing said batches of material into the two compartments of a longitudinally-divided mattress tick, it being immaterial whether 25 the part of the machine through which said batches of material are introduced into the two compartments of the mattress tick is constructed in the form of two separate spouts 30

or one wide spout that is divided into two 35 separate portions.

Having thus described my invention, what I claim as new and desire to secure by Letters Patent is:

1. A mattress filling machine, comprising a bed adapted to receive material which is 40 to be used to fill a mattress tick, means for compressing or compacting said material, a discharge spout that is adapted to be inserted in the open end of said tick, a means for introducing the material into said tick, a 45 removable dividing bar adapted to be arranged on said bed so as to divide the bed into two zones, and spout members on said dividing bar arranged in spaced relation and adapted to be positioned in said spout 50 so as to divide the interior of same into two portions.

2. A mattress filling machine, comprising a bed, a pressing device for compacting or 55 compressing material on said bed, a pusher, a spout at the discharge end of said bed constructed so as to permit the open end of the longitudinally-divided mattress tick or casing to be drawn over same, and a removable dividing bar adapted to be positioned on 60 said bed and provided on its front end with spaced members which are adapted to straddle the seam or dividing element at the center of the mattress tick.

HUBERT C. SMITH.
